UNITED STATES PATENT OFFICE.

GEORGE WILLIAM HIZER, OF DENVER, COLORADO.

CHECKREIN ATTACHMENT.

SPECIFICATION forming part of Letters Patent No. 511,697, dated December 26, 1893.

Application filed March 31, 1893. Serial No. 468,592. (No model.)

To all wh^o may concern:

Be it known that I, GEORGE WILLIAM HIZER, a citizen of the United States of America, residing at Denver, in the county of Arapahoe and State of Colorado, have invented certain new and useful Improvements in Checkrein Attachments; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 My invention relates to an improved checkrein attachment, and consists of the features hereinafter described and claimed, all of which will be fully understood by reference to the accompanying drawings in which is 20 illustrated an embodiment thereof.

In the drawings, Figure 1 shows the attachment in use. Fig. 2 is a plan view in detail. Fig. 3 is an edge view thereof. Fig. 4 is a section taken on the line $x-x$, Figs. 2 and 3. Fig. 5 shows an open harness **D** forming part of the invention.

Similar reference characters indicating corresponding parts or elements of the mechanism in the several views, let the numeral 5 30 designate an endless rubber band provided with open harness **D**'s 6. The band is attached to the **D**'s by passing it through the openings 6^a, edgewise. The rubber band is

covered by a leather sheath 8 which normally extends from one of the **D**'s 6 to the other. 35 One of the **D**'s is provided with a leather eye 7 adapted to connect with the check-hock. The check-rein may be attached to the other **D** or directly to the end of the band as may be desired. The rubber band gives the device the required degree of elasticity while the leather sheath affords protection to the band and holds the two parts in suitable proximity for effective utilization. By means of the open **D**'s, the rubber band may be removed and inserted at pleasure. 45

Having thus described my invention, what I claim is—

As an improved article of manufacture, the herein described yielding attachment for 50 check reins consisting of the endless rubber band provided with open rectangular loops at its extremities, the double portion of the band between the loops being surrounded by a loose leather sheath normally extending from 55 one loop to the other but not attached thereto, one of the loops being provided with an apertured leather tab, substantially as described.

In testimony whereof I affix my signature in 60 presence of two witnesses.

GEORGE WILLIAM HIZER.

Witnesses:

BRINTON GREGORY,
CHAS. E. DAWSON.

It is hereby certified that Letters Patent No. 511,697, granted December 26, 1893, upon the application of George William Hizer, of Denver, Colorado, for an improvement in "Checkrein Attachments," were erroneously issued to said Hizer as sole owner of the invention; that said Letters Patent should have been issued to said *George William Hizer and Elizabeth Richardson, jointly*, each being owner of one-half interest, as shown by the record of assignments in this office; and that said Letters Patent should be read with this correction therein that the same may conform to the record of the case in the Patent Office.

Signed, countersigned, and sealed this 16th day of January, A. D. 1894.

[SEAL.]

JOHN M. REYNOLDS,
Assistant Secretary of the Interior.

Countersigned:

JOHN S. SEYMOUR,
Commissioner of Patents.
